UNITED STATES PATENT OFFICE.

WILLIAM H. WOOLUMS, OF SOUTH BEND, INDIANA.

DESIGN FOR AN AUTOMOBILE SIGNALING DEVICE.

Application filed August 3, 1922. Serial No. 3,275. Term of patent 14 years.

To all whom it may concern:

Be it known that I, WILLIAM H. WOOLUMS, a citizen of the United States, residing at South Bend, in the county of St. Joseph and State of Indiana, have invented a new, original, and ornamental Design for Automobile Signaling Device, of which the following is a specification, reference being had to the accompanying drawing, forming a part thereof.

Figure 1 is a front elevation of an auto-

mobile signaling device showing my new design.

Figure 2 is a rear elevation of the device.

Figure 3 is a top plan view of the device.

I claim:

The ornamental design for an automobile signaling device, as shown.

In testimony whereof I affix my signature.

WILLIAM H. WOOLUMS.
